(57) **CLAIM**

The ornamental design for a personal computer, as shown and described.

DESCRIPTION

FIG. 1 is a perspective view of the front, bottom and right side of a personal computer showing my new design;

FIG. 2 is a right side view thereof; and,

FIG. 3 is an enlarged view thereof at A—A' and B—B' in FIG. 1.

The portions of the article in broken lines are shown for illustrative purposes only and form no part of the claimed design.

1 Claim, 3 Drawing Sheets*FIG. 2*

FIG. 3
